UNITED STATES PATENT OFFICE.

GEORGE E. WOODBURY, SAN FRANCISCO, CALIFORNIA.

STREET-SWEEPING MACHINE.

SPECIFICATION forming part of Letters Patent No. 274,164, dated March 20, 1883.

Application filed May 5, 1882. (No model.)

To all whom it may concern:

Be it known that I, GEORGE E. WOODBURY, of the city and county of San Francisco, in the State of California, have made and invented 5 certain new and useful Improvements in Street-Sweeping Machines; and I do hereby declare that the following is a full, clear, and exact description of the same, reference being had to the accompanying drawings.

10 My invention relates to improvements in machines for cleaning streets.

It has for its object to provide a machine simple in its construction and effective in its operation of gathering, taking up, and collecting 15 dirt and matter required to be removed from the surface of the street and roadways.

The following description explains the invention and the manner of constructing, using, and operating the same.

20 In the drawings herein referred to by letter, Figure 1 is an elevation of a machine constructed according to my invention, the view being a longitudinal section taken through the center of the machine. Fig. 2 is a plan or top 25 view of the machine with the elevator and dirt-box taken off. Fig. 3 is a view in detail, taken from the rear of the elevator, showing the manner of constructing the box or receptacle into which the sweepings are deposited by the 30 elevator. Fig. 4 is a section taken diametrically through one of the rotary brushes. Fig. 5 is a detail showing the cam for the brush-lifting.

A A are the side bars of the machine-frame, 35 in which the two axles b c have bearings. The cross-bars B C at front and rear complete the frame. The side bars are carried upward and together at the front to form an arch or goose-neck, to give room for cramping the front 40 wheels.

The front axle is not attached directly to the frame, but is connected to the end of a central post formed of an upright shaft, D, which has a screw-threaded portion and working 45 through a threaded box, E, in the end of the frame. The lower end of this post rests in a socket in the top of the axle-tree and forms the king-bolt of the front wheels, while the upper end is provided with a hand-wheel, 50 F, by which the post or shaft can be rotated from the driver's seat. The entire frame of

the machine is therefore supported at the front from this single point formed of the box E, and the height of the machine-frame from the surface is readily changed by rotating the post 55 D. This enables the sweeping mechanism to be raised and held out of action, and the working contact of the brushes with the surface beneath to be adjusted as required.

At each side of the frame, and about midway between the two axles, are two short vertical shafts, g g, having a rotary motion. They are held in boxes h h on brackets h' h', bolted to the bars A B of the frame, and the rotary motion is derived from the rear axle through 60 the medium of a driving-gear, H, on the axle, a gear, i, on the shaft g, and a connecting-shaft, I, having gears j j. Bevel-gears are employed at these points to conform to the change in the position of the connected shafts. These upright shafts carry and give motion to a pair of 65 circular brushes, each composed of a set of detached brushes, M M, that form the sweeping or dirt-gathering mechanism of the machine. These brushes move in a horizontal plane, and are driven with uniform speed with rotary motion toward each other by the forward movement of the machine. They act to sweep the matter from each side of the path of the machine and gather it inward and to the center. 70 Being made of large diameter, they project beyond the sides of the machine and act upon a considerable extent of surface.

The brushes M consist of a number of segmental blocks, m, set loosely in recesses in a 75 revolving carrier, K, fixed to the lower end of the shaft g, and they are confined in position without horizontal play or movement, but are free to move independently of one another in a vertical direction in the confining-recess. 80 Each block is provided with a means for holding it down to work against the surface with a yielding pressure, and also for lifting up each one as it passes the center line at the inner side, and holding it up clear of the street-surface while passing around at the rear from the 85 inside to the outside of the machine again. In their movement from the outside inward and toward the center of the machine, therefore, the brushes act against the street-surface; but in their movement back of the center and outward they are lifted and held out of action. 90 95 100

The matter thus gathered into the center from each side is deposited in a windrow behind the two rotating carriers K, as the brushes are lifted. Each revolving carrier K is constructed 5 of a light skeleton frame, consisting of ribs n and inner and outer rims, n'n', the two together inclosing and forming the sides of a number of segmental openings. The ribs n radiate from a central hub, p, into which the lower end of 10 the shaft is fixed. From this hub a number of curved spring-plates, P P, extend outward radially toward the rim of the carrier in position projecting over the center of each brush-compartment, and being secured at the inner 15 ends to the hub; they are connected at the outer ends to the tops of the brush-blocks. Each brush is thus carried on the end of a spring-arm, by which a pressure, more or less yielding according to the power of the springs, 20 is applied upon the top of each brush. While being carried around in the compartments the brushes are capable of a vertical movement independently of one another.

To lift and hold each brush out of action at 25 the required time, the end of the spring-arm P is curved upwardly at the end, and is caused to strike against and ride up over a fixed cam-plate or bar, as the block is carried around to the rear by the revolution of the carrier. This 30 lifting device consists of the concentric plate or bar R, supported from the stationary frame above at several points by curved depend- 35 ing arms or brackets, one of which can be seen at the inner end of the plate where it is secured to the cross-bar B at S, and supports the end r of the plate. The upper face of this plate, at the inner end r, is inclined, so that the end of each spring engaging with this end of the plate shall ride up and pass around to the outer end 40 of the plate, thereby raising up the brush-block and holding it out of action while this contact with the incline continues. After passing to the outside of the machine the end of the spring slips off from the outer end of the fixed incline 45 R, and the brush is brought down into action again. For co-operation with these revolving brushes I employ a means of taking up and removing the matter as it is gathered in a row or heap under the center of the machine. This 50 part of the machine consists of an elevator, T, formed of a number of buckets on an endless band, and moving upward in an inclosed compartment, t, the bottom of which is a receiving-chamber, u, while the top discharges into a box 55 or dirt-receptacle, W. The elevator is therefore immediately over the curved apron v, which forms the bottom of the elevator-compartment. Across the lower edge of this apron an inclined shoe, X, extends downward to the 60 street-surface, and immediately behind it is a horizontal cylindrical brush, Y, having a rotary motion imparted to it in a forward and upward direction. This shoe has an inclined bottom, so that it rides over the row of gathered dirt left behind the circular brushes, while 65 the cylindrical brush works in such proximity to the edge and surface of the shoe that

the matter is caught and thrown upon the curved apron or bottom beneath the elevator-buckets. This shoe is rendered adjustable 70 with respect to the cylindrical brush Y, so that the lower edge can be set up in close relation to the edge of the brush as it decreases by wear of the bristles. For this purpose the shoe is fixed to the ends of two swinging arms, 75 w w, that extend downward and forward from a loose collar on the rear axle. The shoe is then secured to these arms by inserting their ends through slots on the sides of the shoe and fastening them together by set-screws, as 80 shown in detail view, Fig. 1^a. This allows the shoe to be set up closer to the brush when required.

A rear extension, w', of each arm is carried 85 back beneath, and bears against a screw-rod, y, working through a nut in the rear bar, C, of the machine-frame.

The arms, collar, and extension are practi- 90 cally one piece, and by changing the length of these screws the arms can be raised or lowered to throw the brush and shoe to or from the street-surface, or to raise them up altogether out of action.

The elevator-belt travels over pulleys q q, 95 journaled in the sides of the elevator-compartment, and its movement is obtained from the rear axle through the medium of pulleys L L, fixed thereon, and the cross-belts running to the pulleys e² on the lower pulley-shaft.

The cylindrical brush Y is carried on a shaft, 100 e, having bearings in boxes e' e'. The outer ends of this shaft carry pulleys f to receive and be driven by belts d d from hand-wheels l l on the rear axle. All the working parts therefore derive motion from the gears and pulleys in 105 this axle.

The gear and pulley at each side of the ma- 110 chine are fixed together upon a single hub or collar, which turns loosely on the axle, but is connected with and locked by a sliding clutch. 115 This enables the brush-operating mechanism to be readily thrown into and out of action. To enable this to be done from the driver's seat the two clutches o o are connected to the end of a draw-rod, N, by means of two elbow- 120 levers, J J, having their fulcrum at the points J' J', on two fixed brackets on the frame.

Above the rear end of the machine is placed the dirt-receptacle, into which the elevator-buckets discharge the matter raised from the 125 surface below. This receptacle has two divisions or compartments, Z Z, each with an inclined self-discharging bottom, z, and an outlet at the side terminating in a spout. This receptacle is supported at such height above 130 the street-surface that there shall be sufficient room beneath the ends of these discharge-spouts to permit a cart or wagon to draw up closely alongside the machine, and the compartment at that side is easily and quickly emptied of its contents through the inclined spout. These two compartments are arranged to be worked alternately, and as one is filled and is about being emptied through its spout

the elevators are caused to deposit the raised matter into the other compartment. For this purpose the division between the two compartments is carried longitudinally through the center of the receptacle, so that the elevator-buckets discharge directly over it, and then a hinged valve-board, 1, fixed along the top of this dividing line or partition is made to act as a deflector for one compartment or the other, according to the direction into which it sets. Two fixed stops, 2, on the back of the elevator-compartment serve to hold this valve in the inclined position to one side or the other. To operate it from the front of the machine the rod is carried from the hinge of the valve out through the back of the receptacle W, and connection is then made by means of the belt or chain and pulleys with a rod extending forward to the driver's seat.

20 By means of a hand-lever, 3, the rod is rotated and the valve-board readily thrown to the right or left.

This mode of collecting sweepings, and, as the receptacles become filled, discharging their 25 contents into carts to be conveyed away, renders the operation rapid and continuous.

The principle of gathering the dirt by a horizontal sweeping movement into heaps or rows enables such a machine to operate without 30 creating excessive dust and to work with a great degree of cleanliness without scattering.

Having thus fully described my invention, what I claim, and desire to secure by Letters Patent, is—

35 1. In a street-sweeping machine, the combination of a pair of flat horizontally-revolving brushes and vertical shafts thereof, with mechanism connected therewith, and operated by the progression of the machine for giving 40 them a rotary motion toward each other, substantially as described, for the purpose set forth.

2. In a street-sweeping machine, the combination of the circular brushes, each consisting 45 of a set of segmental brush-blocks loosely mounted in a revolving carrier, and mechanism for lifting the detached blocks and holding them up out of action during a portion of each revolution of the carrier, and means, 50 substantially as described, for giving said carriers simultaneously a rotary motion in a horizontal direction, substantially as and for the purpose specified.

3. In a street-sweeping machine, the combination, with a pair of horizontally-revolving circular carriers, each having a set of detached segmental brush-blocks, of means 55 connected thereunto for lifting up and hold-

ing the said blocks out of action at one point and during a portion of each revolution. 60

4. In a street-sweeping machine, the depending brush carrying arms or frame, suspended and fulcrumed from the rear axle, and having bearings for the cylindrical brush, the shoe secured to and capable of adjustment on 65 the lower ends of the arms w and the adjusting-screws on the machine-frame, operating on the opposite end of the lever w, all in combination, substantially as and for the purpose set forth. 70

5. The circular brush mounted in a vertical shaft and adapted to have a horizontal rotary motion, and consisting of a frame or carrier having brush-compartments, a hub carrying vertical spring-arms and a set of brush-blocks 75 attached to the outer ends of the springs, and having vertical play or movement in said compartments, but confined thereon laterally.

6. The horizontally-traveling circular brush consisting of a carrier having a set of brush-blocks mounted loosely thereon, a spring for holding each block with a yielding pressure against the surface beneath, and an inclined piece, R, suspended from the framing and operating on the points of the springs for lifting up each block at one point in the rotation of the carrier, holding it out of action for a portion of such revolution, and then bringing it into contact with the surface again, substantially as described. 85 90

7. The frame A B, mounted on the rear axle, c, and having the screw-threaded box E at the front, in combination with the vertical part, screw-threaded on a portion of its length to work through the said box, and having its 95 lower end slipped in a socket on the center of the front axle, and provided with a hand-wheel on its upper end, substantially as described.

8. In a street-sweeping machine, the combination, with the elevators, of the dirt-receptacle W, having two compartments, each provided with a discharge - spout, the hinged valve or cut-off, and means, substantially as described, for operating said valve or cut-off. 100 105

9. The dirt-receptacle having compartments with inclined self-discharging bottoms z and inclined discharge - spouts, in combination therewith, and the hinged valve or cut-off 1, substantially as described.
